UNITED STATES PATENT OFFICE.

GERALD F. CREAGHAN, OF BANGOR, MAINE.

SCREED.

Application filed February 18, 1924. Serial No. 693,708.

To all whom it may concern:

Be it known that I, GERALD F. CREAGHAN, a subject of the King of Great Britain, residing at Bangor, in the county of Penobscot and State of Maine, have invented new and useful Improvements in Screeds, of which the following is a specification.

This invention relates to improvements in screeds or gauges for concrete construction, 10 an object being to provide means whereby an accurate and uniform thickness of concrete construction may be provided and thus insure a perfectly level surface.

Another object of the invention is the 15 production of a screed which may be used to gauge the surface of rough work or roughing and which may be subsequently adjusted to gauge the surface of the finish.

Another object of the invention is the 20 production of a screed which is simple and economical in construction, may be easily and quickly positioned for use and by means of which screeding and troweling will be facilitated.

25 With the above and other objects in view, the invention further includes the following novel features and details of construction, to be hereinafter more fully described, illustrated in the accompanying drawings and 30 pointed out in the appended claim.

In the drawings:—

Figure 1 is an elevation showing the screed arranged for use.

Figure 2 is a top plan view.

35 Figure 3 is a transverse sectional view on the line 3—3 of Figure 1.

Figure 4 is an enlarged section on the line 4—4 of Figure 3.

40 Figure 5 is a view similar to Figure 3 showing the screed arranged to gauge a finished surface.

Referring to the drawings in detail wherein like characters of reference denote corresponding parts, the reference character 10 indicates a portion of a floor form and 45 supporting members. These members 11 are arranged in spaced relation as shown in Figures 1 and 2 of the drawings and comprise inverted substantially U-shaped frames whose opposite side members have feet 12 extending at an angle therefrom. The supporting members 11 are preferably formed of strips of metal and bent into the shape shown, a number of perforations 13 being provided at the juncture of the feet 50 with the side members of the frame so that

the feet may be easily removed when stripping the floor forms. The members 11 are provided with transverse braces 14.

The members 11 serve as supports for substantially channel-shaped beams 15. These beams are provided with spaced elongated openings 16, by means of which they are adjustably secured to connecting blocks 17, connection being effected through the medium of screws 18. The blocks 17 are connected to the supports 11 by screws 18', the heads of these screws engaging the inclined walls of horizontally arranged grooves 19, while the shanks of the screws have a threaded engagement with openings 20 provided in the upper ends of the supports 11. The grooves 19 extend downwardly for the passage of the shanks of the screws 18. The lower ends of the screws are surrounded by sleeves 21 which are positioned between the tops of the supports and the members 14. These sleeves are preferably made of sheet tin and provide protecting sleeves whereby the screws 18 may be adjusted after the concrete work has been poured.

The screeds may be made of any suitable size and length and each section may include any number of supports. They may be spaced any suitable distance above the floor 85 form, the top surfaces of the screeds providing a gauge for the elevation of the top surface of the roughing, so that this top surface may be accurately and easily leveled. When the floor is removed the feet 12 will 90 separate from the supports 11 due to the perforations 13.

If it is desired to provide a finished surface for the roughing, the screws 18' may be adjusted to elevate the screeds a distance 95 above the top surface of the roughing equal to the desired thickness of the finish. This is clearly illustrated in Figure 5 of the drawings wherein the dotted line *a* indicates the top surface of the roughing while the dotted line *b* indicates the surface of the finish. Adjustment for this purpose is easily effected through the use of a screw driver inserted through the openings 16.

The invention is susceptible of various 105 changes in its form, proportions and minor details of construction and the right is herein reserved to make such changes as properly fall within the scope of the appended claim.

Having described the invention what is 110 claimed is:—

In a screed, spaced inverted substantially

U-shaped supports, channel shaped beams above the supports longitudinal openings, connecting blocks mounted upon the supports, screws carried by the connecting blocks with their heads movably disposed in the longitudinal openings and the said blocks having horizontal grooves with recesses communicating with the grooves, screw members having adjustable connec-

tion with the supports, said screw members 10 having their heads disposed within the grooves of the blocks, whereby the latter may be vertically adjusted and the connection between the channel shaped beams and the supports permitting longitudinal ad- 15 justment.

In testimony whereof I affix my signature.
GERALD F. CREAGHAN.
